UNITED STATES PATENT OFFICE.

LAWRENCE M. PAYNE, OF DAYTONA, FLORIDA.

TOILET-FAN.

1,250,001.

Specification of Letters Patent. Patented Dec. 11, 1917.

Application filed February 24, 1916. Serial No. 80,254.

To all whom it may concern:

Be it known that I, LAWRENCE M. PAYNE, a citizen of the United States, residing at Daytona, in the county of Volusia and State 5 of Florida, have invented certain new and useful Improvements in Toilet-Fans, of which the following is a specification.

My invention relates to fans, and more particularly to a new and improved hand 10 fan.

The primary object of my invention is to provide a fan of the class above mentioned, which is simple in construction, cheap to manufacture, strong and durable, and effective in operation.

Another object of my invention is to provide a fan having a rotary air draft creating element and operating means associated therewith, combined in a structure which 20 may be easily and quickly collapsed into a compact form which may be carried in the pocket of the user.

The improved fan includes a rotary air draft creating element, operating means 25 therefor, and means for automatically disengaging the operating means to afford a continuous rotation of the fan element.

With the above and other objects in view my invention resides preferably in the construction, combination, and arrangement of 30 parts as hereinafter set forth in the specification and illustrated in the accompanying drawings, in which—

Figure 1 is a side elevation of a hand fan embodying the improvements of my invention, the same being shown in position ready 35 for operation.

Fig. 2 is a view of my improved fan showing the same collapsed.

Fig. 3 is an end view of the fan showing the blades and retaining means therefor in section.

Similar reference characters indicate similar parts throughout the various views of 45 the drawings.

In the drawings, wherein the preferred embodiment of my invention is illustrated, I provide a pair of connected arms 1 and 2, said arms being pivoted at adjacent extremities as indicated at 3.

A finger or thumb engaging loop 4 is provided on the arm 1 and the free extremity of said arm is provided with a transverse aperture 5 in which a fan shaft 6 is mounted for rotation. The fan shaft 6 is threaded as at 7, and a pinion 8 is mounted on the

opposite extremity of said shaft. A locking washer 9 is threaded on the shaft 6 and bears lightly against one face of the arm 1, the pinion 8 bearing against the opposite face, 60 said washer and pinion serving to maintain the shaft in the position shown in Fig. 3 so as to prevent lateral movement of the shaft. The fan blades are designated 10 and are placed one upon the other as shown to advantage in Fig. 3, the fans being shown in folded position. It is to be understood, of course, that the fan blades may be curved slightly as is common in the ordinary rotary fan. A retaining nut 11 is receivable 70 upon the threaded portion 7 of the shaft 6, as shown to advantage in Fig. 3, whereby to retain the fan blades in any position to which the same may be placed, whether in folded position or in operating position.

Motion imparting means is provided which includes a rack bar 12 hinged as at 13 adjacent the free extremity of the arm 2. The rack bar, when in use, is in engagement with the pinion 8, as shown to advantage in Fig. 80 1. Means is provided on the arm 2 to automatically engage and disengage said rack bar with the pinion, this means including a connecting rod 14 pivotally secured at 15 to the rack bar 12 and having the opposite 85 extremity connected at 16 to a handle 17 pivoted at 18. The handle 17 is provided with a loop portion 19 for a purpose which will hereinafter appear. Suitable limiting means is provided for the arms 1 and 2 90 which includes a flexible element such as a chain or the like 20.

In operation the arms 1 and 2 are gripped in one hand, the loop 4 being adapted to receive the thumb of the user's hand and the 95 loop 19 being adapted to receive a finger of the user's hand. When a gripping action is exerted on the arms 1 and 2, the handle 17 will be moved on its pivot 18 toward the arm 2 causing a longitudinal pull to be directed on the rack bar 12 bringing the same into engagement with the pinion 8. The arms 1 and 2 may now be contracted by continuing the gripping action, and the rack bar by virtue of its movement over the pinion 8 will cause the same to rotate, generating a strong air draft by means of the fan element. It is, of course, understood that the fan blades are first adjusted to the position shown in Fig. 1 so that it may perform the function of an ordinary rotary fan. When the arms 1 and 2 have approached each other due to the

gripping operation, the same are released, and by spreading the thumb and the fingers of the hand, the arms 1 and 2 will be caused to separate. This automatically disengages 5 the rack bar 12 from the pinion 8 and allows the fan to rotate by momentum until the next impulse can be given. Attention is called to the peculiar shape of the teeth of the rack bar and pinion, this shape of teeth being 10 preferable since it facilitates engagement of the said teeth at any point during the operation, and also facilitates disengagement.

From the above description, taken in connection with the accompanying drawings, it 15 is thought that a clear and comprehensive understanding of the construction, use, and advantages of my invention may be readily gathered, and it will be understood that I desire to reserve the right to make such 20 changes in the detail structure of the invention as do not depart from the spirit and scope of the invention as claimed.

What is claimed is:

1. A hand fan, including a pair of gripping arms pivoted at adjacent extremities, a fan shaft on one arm, a pinion on the shaft, and motion imparting means on the other of said arms adapted to engage and disengage 25 the pinion alternately as the arms are operated, whereby to impart continuous rotary motion to said fan shaft.

2. A hand fan, including gripping arms pivoted at adjacent extremities, a rotary fan element on one of said arms, motion imparting means on the other of said arms, gripping handles on said arms, one of said gripping handles having engagement with said motion imparting means, whereby to automatically move said motion imparting means 35 into and out of operative position.

3. A fan including a pair of gripping arms pivoted together, a fan shaft fulcrumed on one of the arms, said shaft having a gear and a fan, finger engaging means 40 on each arm, a rack bar pivoted to another of the arms said rack bar being adapted to

engage the gear, a connecting rod between the rack bar and one of the finger engaging grips for drawing the rack bar into engagement with the gear when the arms are 50 pressed together, and flexible limiting means for limiting the separation of the arms.

4. A fan including a pair of arms pivoted together, a fan shaft including a gear and a fan, said shaft being journaled in one of the 55 arms, a rack bar fulcrumed on another of the arms having teeth adapted to engage the gear, a fixed thumb piece on one fan arm, a pivoted finger piece on the other arm, a chain connected to the arms for limiting the 60 separation of the arms, and a connection between the pivoted finger piece and the rack bar whereby the rack bar is pressed into engagement with the gear when the arms are pressed together, and moved out of engagement with the gear when the arms are separated.

5. A fan including a pair of pivoted relatively diverging arms, a fan and pinion revolvably mounted on one arm, fan rotating 70 means on the other arm, and means for causing the engagement of the rotating means with the pinion when the arms are pressed together, said means automatically effecting the disengagement of said rotating means 75 and pinion when the arms are separated.

6. A fan including a pair of pivoted relatively diverging arms, a fan on one arm, a fan actuating means on the other arm, and means for causing the simultaneous engagement and operation of the fan by the actuating means when the arms are pressed together, said means automatically causing the disengagement of the actuating means when 80 the arms are separated.

In testimony whereof I affix my signature in presence of two witnesses.

LAWRENCE M. PAYNE.
